CLAIM

The ornamental design for a body portion of an automobile, as shown and described.

DESCRIPTION

FIG. 1 is a front perspective view of a body portion of an automobile showing our new design;

FIG. 2 is a rear perspective view thereof;

FIG. 3 is a front view thereof;

FIG. 4 is a rear view thereof;

FIG. 5 is a left side elevation view thereof, the right side elevation view being a mirror image thereof; and,

FIG. 6 is a top plan view thereof.

The de-emphasized and halftone portions shown in the drawings illustrate environmental structure for the body portion of an automobile that form no part of claimed design.

1 Claim, 5 Drawing Sheets
